CLAIM

The ornamental design for a wireless headphone, as shown and described.

DESCRIPTION

FIG. 1 is a front left perspective view for a wireless headphone, showing my new design;
 FIG. 2 is a front elevational view of FIG. 1 thereof;
 FIG. 3 is a rear elevational view of FIG. 1 thereof;
 FIG. 4 is a left side elevational view of FIG. 1 thereof;
 FIG. 5 is a right side elevational view of FIG. 1 thereof;
 FIG. 6 is a top plan view of FIG. 1 thereof; and,
 FIG. 7 is a bottom plan view of FIG. 1 thereof.
